(Cl. D10—9)

To all whom it may concern:

Be it known that I, Rudolph A. Fritz, a citizen of the United States, residing at Cheviot, county of Hamilton, and State of Ohio, have invented a new, original, and ornamental Design for an Adjustable Hinge of which the following is a specification, reference being had to the accompanying drawings, forming part thereof.

Fig. 1 is a front elevation of an adjustable hinge showing my new design.

Fig. 2 is a top plan of the adjustable hinge of Fig. 1.

Fig. 3 is an elevation of the left end of the adjustable hinge of Fig. 1.

Fig. 4 is an elevation of the right end of the adjustable hinge of Fig. 1.

Fig. 5 is a perspective view of the adjustable hinge of Fig. 1 in open position.

I claim:

The ornamental design for an adjustable hinge, as shown.
